UNITED STATES PATENT OFFICE.

JESSE D. LANGDON, OF LOS ANGELES, CALIFORNIA, ASSIGNOR TO PETROLEUM MACHINERY DEVELOPMENT CORPORATION, OF RENO, NEVADA.

DEEP-WELL PUMP.

Application filed August 4, 1926. Serial No. 127,099.

The present invention relates to deep well pumps, and aims to provide novel and improved means for pumping oil, water or other liquid from a deep well in a practical and efficient manner.

Another object of the invention is the provision of a device of the character indicated having a liquid outlet pipe extending down into the well casing and means for alternately creating pressures within the casing below and above atmospheric pressure, in order to alternately lift the liquid into the casing and force same from the casing through said pipe.

A further object of the invention is the utilization of steam to create pressure within the well casing for forcing the liquid therefrom, and the withdrawal of the steam from the casing for lifting the liquid into the casing under a partial vacuum, and to enable the steam to be condensed and the water of condensation returned to the steam boiler, for purpose of economy, if desired.

A still further object is the provision of novel means for automatically controlling the flow of steam or other pressure fluid to the well casing and vacuum pump, so that when there is no further flow of liquid from the well under fluid pressure within the well casing, the pressure fluid is shut off from the well casing and the vacuum pump then operated by the steam or pressure fluid to create a partial vacuum in the casing for raising the liquid therein.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawing, wherein—

Figure 1 is a vertical section of one form of apparatus, portions being broken away and portions shown in elevation.

Fig. 2 is a similar view illustrating a modification.

In carrying out the invention a tubular casing 7, which may be composed of pipe sections as usual, extends down into the well to the stratum containing the oil, water or other liquid, and said casing has a

partition 8 therein near its upper end providing a discharge chamber 9 above said partition. A liquid outlet pipe 10 extends down into the well within the casing 7 to a point near the lower end of the casing, and projects upwardly through the partition 8 into the chamber 9. The pipe 10 has a valve seat 11 at its upper end on which a ball valve 12 is seatable, to provide a check valve permitting the upward flow of liquid through the pipe 10 into the chamber 9 but preventing the downward flow of liquid. The valve seat 11 has a cage 13 over the valve 12. The chamber 9 is provided at one side between the top and bottom thereof with a liquid outlet 14 from which a pipe 15 extends to a storage tank.

A vacuum pipe 16 is connected to the partition 8 to communicate with the upper end of the well, and is extended through the wall of the chamber 9, as shown.

A steam or pressure fluid chamber 17 is provided above the chamber 9, and a supply pipe 18 is connected to the chamber 17. It is preferable to use steam supplied by a suitable steam boiler, although compressed air or other pressure fluid may be used. A pipe 19 extends through the chamber 9 is connected to the partition 8 and the partition between the chambers 9 and 17, for establishing communication between the pressure fluid chamber 17 and the well. A steam or pressure fluid pipe 20 is connected to the chamber 17 and leads to a steam or pressure fluid engine operating a vacuum pump 33 to which the pipe 16 extends, so that the pump is operated by the steam or pressure fluid flowing through the pipe 20 for pumping the steam or fluid through the pipe 16 from the well.

The chamber 17 has valve seats 21 and 22 at the adjacent ends of the pipes 19 and 20, against which valves 23 and 24 are seatable alternately, said valves having a common stem connecting them. A lever 25 is pivoted on a rock shaft 26 within the chamber 17 and extends between the valve 24 and a collar 27 threaded on the stem of the valves 23, 24 for alternately seating said valves. A rod 28 is pivoted to said lever and passes slidably through the partition between the chambers 9 and 17 and is connected to a float 29 movable in the chamber 9 above the outlet 14. Thus, the valves 23, 24 are float-controlled.

In order to protect the control of the valves 23, 24, a baffle plate 30 is disposed within the chamber 9 at a level immediately above the outlet 14, with a slight clearance 5 between the edges of the plate and wall of the chamber 9 so that the liquid may be forced upwardly in said chamber above said plate, as illustrated in the drawing. The plate 30, as shown, is supported from the 10 partition 8 on posts 31.

A handle or lever 32, as shown, is secured on the rock shaft 26 on the exterior of the chamber 17 for manually or otherwise moving the valves 23, 24.

In operation, supposing the liquid to be lifted into the casing 7, as shown, and the handle or lever 32 to be operated manually or otherwise to raise the valve 24 against its seat 22 and unseat the valve 23, the steam 15 will flow from the chamber 17 through the pipe 19 into the well, thereby creating pressure in the well and forcing the liquid therein downwardly in the casing 7 and upwardly through the pipe 10 into the chamber 9. The 20 liquid flowing into the chamber 9 faster than it passes from said chamber through the pipe 15, will result in the level of the liquid in the chamber 9 rising above the baffle plate 30, as shown, thereby supporting the float 25 and keeping the valve 24 closed and the valve 23 open. The liquid in the well is thus forced therefrom under pressure, and when the flow of liquid from the well through the pipe 10 is stopped, the level of 30 the liquid in the chamber 9 will move down, inasmuch as the liquid in the chamber 9 above the baffle plate 30 will drain down through the outlet 14. The baffle plate 30 also prevents the steam which may flow up- 35 wardly through the pipe 10 from impinging against the float 29 and holding same in raised position. Consequently, when the discharge of the liquid is stopped, such as when the level of the liquid in the casing 7 reaches the lower end of the pipe 10, the 40 float 29 will move downwardly, and the weight thereof will swing the lever 25 downwardly, thereby opening the valve 24 and closing the valve 23. This will shut off the steam from the well, and the steam will now 45 flow from the chamber 17 through the pipe 20 to the vacuum pump 33, thereby automatically starting the pump, so that the steam within the casing 7 is pumped through 50 the pipe 16. This will create a partial vacuum in the casing 7 to lift the liquid therein, the check valve 12 preventing the liquid in the pipe 10 from moving downwardly. The steam which is pumped from the well casing 55 may be condensed and the water of condensation returned to the boiler, as a conservation measure. There is no appreciable condensation of the steam within the well casing, owing to the fact that there is little 60 or no loss of heat units within the well. 65

After the liquid is thus pumped into the well casing, the valves 23, 24 are reversed to the position illustrated, to again start the discharge of the liquid from the well as hereinbefore described. This may be done 70 by manually or otherwise operating the lever or handle 32 at intervals, or the lever may be moved by hand or otherwise to raise the valves 23, 24 after the vacuum pump 33 has been operated a predetermined length of 75 time. Thus, after a predetermined number of revolutions of a shaft of the pump 33 the lever 32 may be moved to raise the valves 23, 24.

In the modification shown in Fig. 2, the 80 well casing 7' has a head or cap 8', and the liquid discharge pipe 10' extends through said head. A pipe 34 depends from the head 8' within the casing 7' to a point near the lower end thereof, and the lower portion thereof serves as a cylinder for a piston 35 movable vertically within said pipe. The piston 35 has a piston plunger 36 of smaller diameter working within a cylinder 37 screw-threaded on and depending from the lower end of the pipe 10'. A check valve 12' is provided within the lower end of the pipe 10' and a similar valve 39 is provided within the upper end portion of the piston plunger 36, permitting the upward flow of 85 liquid but preventing the downward flow thereof. The pipe 34 has stops 40 at its lower end to limit the downward movement of the piston 35 and the plunger 38 has a passage or opening extending longitudinally 90 therethrough to establish communication between the cylinder 37 and lower portion of the pipe 34 below the piston 35. 95

The steam or pressure fluid supply pipe 18' is connected to the head 8' in communication with the annular chamber 46 between the casing 7' and pipe 34, and another steam or pressure fluid supply pipe 41 is connected to the head 8' in communication with the chamber 47 between the pipes 10' and 34. 105 Similarly, vacuum pipes 16' and 43 leading to a vacuum pump are connected to the head 8' in communication with the respective chambers 46 and 47. The pipes 18', 41, 43 and 16' have the respective valves 23', 42, 110 44 and 45 to be controlled by hand or otherwise. 115

In operation, with the valves 42 and 45 open and the valves 23' and 24' closed, steam is admitted into the chamber 47 while the steam in the chamber 46 is pumped therefrom through the pipe 16'. As a result, the liquid is lifted into the chamber 46 and, simultaneously, the piston 35 is moved downwardly within the pipe 34 by the steam in the chamber 47. When the piston 35 is moved downwardly liquid will flow upwardly through the piston plunger 38 into the cylinder 37, the valve 39 opening upwardly 120 while the valve 12' supports the liquid in 125 130

the pipe 10'. Now, by closing the valves 42 and 45 and opening the valves 23' and 44, steam is admitted into the chamber 46 while the steam in the chamber 47 is drawn therefrom through the pipe 43 to the vacuum pump. Thus, the vacuum within the chamber 47 and pressure within the chamber 46 effective upwardly within the lower portion of the pipe 34 will force the piston 35 upwardly, the pressure above and below said piston being below and above atmospheric pressure. Therefore, the liquid in the cylinder 37 above the valve 39 is forced upwardly through the pipe 10' past the valve 12'. The operation is then repeated as before, and when the valves 23' and 44 are closed and the valves 42 and 45 opened, the pressure on the piston 35 below and above same will be above and below atmospheric pressure. In this way, the piston 35 is moved both upwardly and downwardly by pressures on opposite sides thereof below and above atmospheric pressure working in unison. With either form of apparatus, it will be noted that there is no substantial loss in heat units so that the use of steam will be efficient, and the use of a partial vacuum in withdrawing the steam from the well will also provide for efficiency. The steam may be condensed and the water of condensation returned at almost the boiling point to the boiler so as to conserve fuel for heating the boiler.

Having thus described the invention, what is claimed as new is:—

1. A deep well pump comprising a deep well casing, a liquid outlet pipe within said casing, means for admitting steam into said casing for forcing liquid from the casing through said pipe, a steam operated pump for withdrawing the steam from the casing to lift liquid into the casing, and means for alternately supplying steam to the first-named means and pump.

2. A deep well pump comprising a well casing, a liquid outlet pipe therein, means for admitting pressure fluid into the casing to force liquid from the casing through the outlet pipe, a vacuum pump connected to the casing to pump the fluid from the casing for lifting liquid into the casing, and automatic means operable, when the discharge of liquid through the outlet pipe ceases, for shutting off the flow of pressure fluid from the casing and starting said pump.

3. A deep well pump comprising a well casing, a liquid outlet pipe therein, means for admitting pressure fluid into the casing to force liquid from the casing through the outlet pipe, a vacuum pump connected to the casing to pump the fluid from the casing for lifting liquid into the casing and operated by fluid pressure, and automatic means operable, when the discharge of liquid through the outlet pipe ceases, for shutting off the

pressure fluid from the casing and establishing the flow of pressure fluid to said pump for operating same.

4. A deep well pump comprising a well casing, a liquid outlet pipe therein, means for admitting pressure fluid into the casing to force the liquid from the casing through the outlet pipe, a pressure fluid operated vacuum pump connected to the casing to pump the fluid from the casing for lifting liquid into the casing, valve means for alternately shutting off the flow of pressure fluid to the casing and pump, and automatic means controlling said valve means and operable, when the discharge of liquid through the outlet pipe ceases, for operating said valve means to shut off the flow of pressure fluid from the casing and establish the flow of pressure fluid to said pump.

5. A deep well pump comprising a well casing, a discharge chamber having an outlet, a liquid outlet pipe within the casing and arranged to discharge liquid into said chamber, means for admitting pressure fluid into the casing to force liquid from the casing through the outlet pipe into said chamber, a vacuum pump connected to the casing to pump the fluid from the casing for lifting liquid into the casing, a float in said chamber above the level of said outlet to be held in raised position by the liquid in said chamber when above the level of said outlet, and means controlled by said float for shutting off the flow of pressure fluid from the casing and starting said pump when said float moves downwardly by the lowering of the level of the liquid in said chamber.

6. A deep well comprising a well casing, a liquid outlet pipe therein, a chamber communicating with said pipe and arranged to hold liquid therein at an elevated level during the forcing of liquid through said pipe, means for admitting pressure fluid into said casing to force the liquid from the casing through said outlet pipe, a vacuum pump connected to the casing to pump the fluid from the casing for lifting the liquid into the casing, a float in said chamber, and means controlled by said float whereby the float in moving downwardly will shut off the pressure fluid from the casing and will start the pump.

7. A deep well pump comprising a well casing, a liquid outlet pipe therein, a chamber communicating with said pipe and so arranged that the liquid level therein is raised when liquid is forced through said pipe from the casing, means for admitting pressure fluid into the casing to force liquid from the casing through the outlet pipe, a pressure fluid operated vacuum pump connected to the casing to pump the fluid from the casing for lifting liquid into the casing, valve means for alternately shutting off the flow of pressure fluid from the casing and

4
pump, and a float in said chamber controlling said valve means for operating the valve means to shut off the pressure fluid from the casing and establish the flow of pressure fluid to the pump when said float moves downwardly in said chamber.

8. A deep well pump comprising a well casing, a discharge chamber having an outlet between the top and bottom thereof, a liquid outlet pipe within the casing extending upwardly into said chamber and having a check valve, means for admitting pressure fluid into the casing to force liquid from the casing through the outlet pipe into said chamber, a float in said chamber at a higher level than said outlet, valve means controlled by said float for shutting off the flow of pressure fluid from the casing when said float moves downwardly, a baffle plate in said chamber above said pipe and below the float, and means for the discharge of the pressure fluid from the casing.

9. A deep well pump comprising a well casing, a liquid outlet pipe leading therefrom, a chamber communicating with said pipe to receive the liquid therefrom and having an outlet so arranged that when the liquid flows into said chamber from said pipe it rises to a level above said outlet and when pressure fluid enters said chamber from said pipe the liquid level in the chamber

ber falls to said outlet, means for admitting pressure fluid into the casing to force the liquid from the casing through the outlet pipe into said chamber, automatic means controlled by the liquid in the chamber above said outlet and operable for shutting off the flow of pressure fluid into the casing when the liquid level in said chamber falls to said outlet, and means for the discharge of the pressure fluid from the casing.

10. A deep well pump comprising a well casing, a liquid outlet pipe leading therefrom, a chamber communicating with said pipe to receive the liquid therefrom and having an outlet so arranged that the liquid from the pipe flows through the chamber to the outlet and that the liquid level in the chamber rises above said outlet during such flow of liquid, means for admitting pressure fluid into the casing to force the liquid from the casing through said outlet pipe, a float in said chamber, valve means controlled by said float for shutting off the flow of pressure fluid into the casing when said float moves downwardly by the falling of the liquid level in said chamber to said outlet, and means for the discharge of the pressure fluid from the casing.

In testimony whereof I hereunto affix my signature.

JESSE D. LANGDON.
